BOAT PROPULSION APPARATUS

Hardy H. Raulerson, Long Beach, Calif.

Application January 13, 1945, Serial No. 572,655

9 Claims. (Cl. 115—24)

This invention relates to a boat propulsion apparatus.

The general object of the invention is to provide a novel apparatus for providing rotary driving motion from a pivoted member.

A more specific object of the invention is to provide a boat propelling apparatus including a pivoted operating arm and novel means connecting the arm to a propeller for driving a boat.

A further object of the invention is to provide a boat propelling apparatus including a pivoted operating member and wherein means is provided which is operative during a portion of the movement of the member to simultaneously drive a propeller and energize a spring device which latter serves to drive the propeller during another portion of the movement of the operating member.

A further object of the invention is to provide a novel drive mechanism for a boat propeller.

Another object of the invention is to provide a boat propelling apparatus including novel means for driving and feathering a propeller.

Other objects and advantages of the invention will be apparent from the following description taken in connection with the accompanying drawings, wherein:

Fig. 1 is a top plan view of a boat propulsion apparatus embodying the features of my invention;

Fig. 2 is a section partly in side elevation view, and taken substantially on line 2—2 of Fig. 1;

Fig. 3 is an enlarged sectional view of a portion of the propeller pitch changing device taken on line 3—3, Fig. 1;

Fig. 4 is a front elevation of the propeller taken on line 4—4, Fig. 1;

Fig. 5 is an enlarged sectional view of the propeller hub and the pitch changing mechanism as enclosed therein and taken on line 5—5, Fig. 1;

Fig. 6 is a section taken on line 6—6, Fig. 5;

Fig. 7 is an enlarged section taken on line 7—7, Fig. 1;

Fig. 8 is a transverse section taken on line 8—8, Fig. 7, and

Fig. 9 is a section taken on line 9—9, Fig. 6.

Referring to the drawings by reference characters, I have shown my invention as embodied in a boat propulsion apparatus which is indicated generally as at 10. As shown, the device includes a frame having end walls 11, side walls 12, and a bottom 13. Journalled in suitable bearings 14 on the side walls 12, I provide a shaft 15 which

has an operating handle 16 rigidly secured thereto. A crank arm 17 is fixed on the outer end of the shaft 15 and is attached to one end of a link 18. The other end of the link 18 is attached to a crank 19 which is fixed on a shaft 20. The shaft 20 has a bevel gear 21 thereon which drives a pinion gear 22 on a hollow shaft 23. The shaft 23 passes through a hole 24 in the adjacent end wall 11 and has a propeller indicated generally at 24' mounted thereon.

A spur gear 25 attached to the shaft 20 is adapted to drive a smaller spur gear 26 which has a crank arm 27 thereon. One end of a cable 28 is attached to the crank arm 27 and runs over and has the other end attached to a segmental pulley 29 mounted on a shaft 30, journaled in the side walls 12 of the frame 10.

An eccentric cam pulley 31, also mounted on the shaft 30 supports another cable 32 which has its inner end attached to one end of a tension spring 33, the other end of the spring being fixed to a cable 34 which is fastened as at 35 to the lower end of a pitch changing lever 36 mounted on a shaft 37 which is rotatably supported in bearing 37' on the side walls 12 of the frame.

A pair of arms 38 are attached at one end to the shaft 37 as at 39, and have their other ends attached to clamps 40 at 41. The clamps 40 are fixed to the outer race A of a bearing 42. The inner race B of the bearing is fixed to a sleeve 43, which is slidably supported on the shaft 23, and upon movement of the lever 36 and the arms 38, a rod 44, enclosed within the hollow shaft 23, may be moved back and forth through a connection between the sleeve 43 and the rod 44, consisting of a pin 45 that slides in a slot 46 in the shaft 23. This structure is clearly shown in Fig. 7.

The propeller 24' includes a hub 50, having a rear streamlined portion 51, and a forward portion 52, which threadedly engages the rear end of the shaft 23 as at 53. Reaction blades 54 and 55 are mounted on the portion 52, and have inwardly extending shafts 56 which are held in alignment by a sleeve 57. Outward of the sleeve 57, I provide S-shaped crank arms 58 and 59 which may be attached to links 60 and 61 which are pivotally pinned to the rearward end of the rod 44 as at 62. The cranks 58 and 59 are held against rotation by means of pins 63 and 64 which also serve to retain the shafts 56 in position. Packing glands may be provided for the blades as shown at 65 and for the members 51 and 52 as shown at 67.

To hold the lever 36 in adjusted position, I provide a toothed rack 70 (Fig. 3) which is engaged by a dog 71 pivoted at 72 to the lever 36 and urged to seated position by a spring 73.

The gear 26 is one-half the diameter of the gear 25 so that a ratio of 2:1 is provided.

As shown, the shaft 15 has an arm 75 depending therefrom. One end of a spring 76 is secured to this arm 75 while the other end of the spring is secured to the adjacent end wall 11.

Secured to the lower end of the lever 36 I provide a spring 77. The spring 77 is connected as at 78 to the adjacent end wall 11.

In operation it will be seen that upon a back and forth motion of the lever 16 the gear 21 may be driven through the rod 18 and the crank 19 to drive the propeller 24'. The construction of the gears 25 and 26, the pulleys 29 and 31 and the spring 33 is such that approximately half the energy at the lever 16 is transferred to the spring and the other half is put into the propeller. This energy in the spring is returned to the drive shaft at the extreme forward and back positions of the lever 16. This will cause a counterbalancing effect to make for ease in operating the mechanism.

The pitch of the blades may be varied by moving the rod 44 whereupon the arms 60 and 61 will cause the crank arms 58 and 59 to rotate the shafts 56 and in turn the blades 54 and 55, to any predetermined position.

The movement of the lever 36 to adjust the propeller pitch also simultaneously reduces or increases the tension on the spring 33 depending upon the direction of movement of the rod. This prevents a sudden change in the amount of power required to operate the lever 16 when the pitch of the propeller 24' is altered.

In operation the propeller 24' is arranged at the rear of the boat and the handle 16 moves to the left in Fig. 2 when pulled by the operator and moves to the right in Fig. 2 when pushed by the operator. During the pulling of this handle 16 the pull of the spring 76 is increased and this increased pull is given up when the handle 16 is pushed forwardly. It is a well recognized fact that a person can pull a lever more readily than he can push it and the spring 76 tends to compensate for this difference.

The tension of the spring 77 and spring 33 when the lever 36 is vertical, as shown in Fig. 2, is even. Thus the pull of the cable 34 on the lower end of the lever 36 is largely taken up by the spring 77. When the lever 36 is shifted forwardly or backwardly to change the pitch, the balance between the springs 33 and 77 permits such shifting of the lever to be easily accomplished.

With the eccentric action described I secure an even flow of power at the point of traction. As a result there is no pulsating load and there are no points of dead center and therefore the efficiency of the operator is increased. With my construction an action similar to that of a fly wheel is produced with an even flow of power to the drive shaft and this constant flow of power to the drive shaft increases the efficiency.

Having thus described my invention and the present preferred embodiments thereof, I desire to emphasize the fact that many modifications may be resorted to in a manner limited only by a just interpretation of the following claims.

Having thus described my invention, I claim:

1. A boat propulsion apparatus including a

drive shaft, manual means for rotating said drive shaft, a propeller shaft, means for driving said propeller shaft from said drive shaft, a second shaft, means operated by the drive shaft for oscillating the second shaft, a cam member on said second shaft, said cam member including a cam portion having a spiral working surface, a flexible member anchored to said cam member and engaging the working surface of said cam, a resilient member having one end connected to said flexible member, means to anchor the other end of said resilient member, and a propeller on said propeller shaft.

2. A propulsion apparatus including a drive shaft, manual means for rotating said drive shaft, a propeller shaft, means for driving said propeller shaft from said drive shaft, crank means, means to drive the crank means at twice the speed of the drive shaft, a second shaft, a cam member on said second shaft, said cam member including a cam portion having a spiral working surface, a flexible member anchored to said cam member and engaging the working surface of said cam, a resilient member having one end connected to said flexible member, means to anchor the other end of said resilient member, a pulley on said second shaft, and a second flexible member having one end connected to the pulley and the other end connected to said crank means, the relation of said cam working surface and said crank means being such that when the crank means is nearest to the second shaft the second flexible member operatively engages the portion of the cam most remote from its axis and approaches its axis as the crank means recedes from the second shaft.

3. A boat propulsion apparatus including a drive shaft, manual means for rotating said drive shaft, a propeller shaft, means for driving said propeller shaft from said drive shaft, crank

means, means to drive the crank means at twice the speed of the drive shaft, a second shaft, a cam member on said second shaft, said cam member including a cam portion having a spiral working surface, a flexible member anchored to said cam member and engaging the working surface of said cam, a resilient member having one end connected to said flexible member, a shiftable anchor member, means to connect the other end of said resilient member to said anchor member, a pulley on said second shaft, a second flexible member having one end connected to the pulley and the other end connected to said crank means, the relation of said cam working surface and said crank means being such that when the crank means is nearest to the second shaft the second flexible member operatively engages the portion of the cam most remote from its axis and approaches its axis as the crank means recedes from the second shaft, and a propeller on said propeller shaft.

4. A boat propulsion apparatus including a manually operable actuating member, a drive shaft remote from the actuating member, means driven by said member for rotating said drive shaft, a propeller shaft, means on said drive shaft for driving said propeller shaft, crank means, means to drive the crank means at twice the speed of the drive shaft, a second shaft, a cam member on said second shaft, said cam member including a cam portion having a spiral working surface, a flexible member anchored to said cam member and engaging the working surface of said cam, a resilient member having one end connected to said flexible member, a pivoted arm, means to anchor the other end of said resilient member to said arm, a pulley on said second

shaft, a second flexible member having one end connected to the pulley and the other end connected to said crank means, the relation of said cam working surface and said crank means being such that when the crank means is nearest to the second shaft the second flexible member operatively engages the portion of the cam most remote from its axis and approaches its axis as the crank means recedes from the second shaft, and a propeller on said propeller shaft.

5. A boat propulsion apparatus including a pivoted operating lever, a drive shaft remote from the lever, means driven by said lever for rotating said drive shaft, a propeller shaft, means on said drive shaft for driving said propeller shaft, crank means, means to drive the crank means at twice the speed of the drive shaft, a second shaft, a cam member on said second shaft, said cam member including a cam portion having a spiral working surface, a flexible member anchored to said cam member and engaging the working surface of said cam, a resilient member having one end connected to said flexible member, a pivoted arm, means to connect the other end of said resilient member to said arm, a pulley on said second shaft, a second flexible member having one end connected to the pulley and the other end connected to said crank means, the relation of said cam working surface and said crank means being such that when the crank means is nearest to the second shaft the second flexible member operatively engages the portion of the cam most remote from its axis and approaches its axis as the crank means recedes from the second shaft, and a propeller on said propeller shaft.

6. A boat propulsion apparatus including a pivoted operating lever, a drive shaft remote from the lever, means driven by said lever for rotating said drive shaft, a propeller shaft, means on said drive shaft for driving said propeller shaft, crank means, means to drive the crank means at twice the speed of the drive shaft, a second shaft, a cam member on said second shaft, said cam member including a cam portion having a working surface, a flexible member anchored to said cam member and engaging the working surface of said cam, a resilient member having one end connected to said flexible member, a pivoted arm, means to connect the other end of said resilient member to said arm, a pulley on said second shaft, a second flexible member having one end connected to the pulley and the other end connected to said crank means, the relation of said cam working surface and said crank means being such that when the crank means is nearest to the second shaft the second flexible member operatively engages the portion of the cam most remote from its axis and approaches its axis as the crank means recedes from the second shaft, a propeller on said propeller shaft, said propeller including a hollow hub portion having feathering reaction blades independently rotatable thereon, means to feather each blade, and means connecting said feathering means to said pivoted arm.

7. A boat propulsion apparatus including a pivoted operating lever, a drive shaft remote from the lever, means driven by said lever for rotating said drive shaft, a propeller shaft, means on said drive shaft for driving said propeller shaft, a gear secured on said drive shaft, another gear driven by said first gear, said other gear being of one-half the diameter of the first gear, crank means driven by said other gear, a second shaft remote from said first shaft, a cam member on said second shaft, said cam member including

a cam portion having a spiral working surface, a flexible member anchored to said cam member and engaging the working surface of said cam, a resilient member having one end connected to said flexible member, a pivoted arm, means to connect the other end of said resilient member to said arm, a pulley on said second shaft, a second flexible member having one end connected to the pulley and the other end connected to said crank means, the relation of said cam working surface and said crank means being such that when the crank means is nearest to the second shaft the second flexible member operatively engages the portion of the cam most remote from its axis and approaches its axis as the crank means recedes from the second shaft, a propeller on said propeller shaft, said propeller including a hollow hub portion having feathering reaction blades independently rotatable thereon, means to feather each blade, and means connecting said feathering means to said pivoted arm.

8. A boat propulsion apparatus including a pivoted operating lever, a drive shaft remote from the lever, crank means driven by said lever for rotating said drive shaft, a gear on said drive shaft, a propeller shaft, a gear on said propeller shaft and meshing with said first gear, a third gear, said third gear being secured on said drive shaft, a fourth gear driven by said third gear, said fourth gear being of one-half the diameter of the third gear, other crank means driven by said fourth gear, a second shaft remote from said first shaft, a cam member on said second shaft, said cam member including a cam portion having a spiral working surface, a flexible member anchored to said cam member and engaging the working surface of said cam, a resilient member having one end connected to said flexible member, a pivoted arm, means to connect the other end of said resilient member to said arm, a segmental pulley on said second shaft, a second flexible member disposed in said pulley groove and having one end connected to the pulley and the other end connected to said other crank means, the relation of said cam working surface and said other crank means being such that when the other crank means is nearest to the second shaft the second flexible member operatively engages the portion of the cam most remote from its axis and approaches its axis as the other crank means recedes from the second shaft, a propeller on said propeller shaft, said propeller including a hollow hub portion having a pair of axially aligned blade shafts thereon, a feathering reaction blade mounted on each blade shaft, a crank arm on each blade shaft, said propeller shaft being hollow, a rod being mounted to move in said hollow propeller shaft, a pair of links pivoted to the rod and pivoted to the crank arms, and means connecting said rod to said pivoted arm.

9. A boat propulsion apparatus including a pivoted operating lever, a drive shaft remote from the lever, crank means driven by said lever for rotating said drive shaft, a gear on said drive shaft, a propeller shaft, a gear on said propeller shaft and meshing with said first gear, a third gear secured on said drive shaft, a fourth gear driven by said third gear, said fourth gear being of one-half the diameter of the third gear, other crank means driven by said fourth gear, a second shaft remote from said first shaft, a cam member on said second shaft, said cam member including a cam portion having a spiral working surface diminishing towards its axis, a flexible

member anchored to said cam member and engaging the working surface of said cam, a resilient member having one end connected to said flexible member, a pivoted arm, means to connect the other end of said resilient member to said arm, a segmental grooved pulley on said second shaft, a second flexible member disposed in said pulley groove and having one end connected to the pulley and having the other end connected to said other crank means, the relation of said cam working surface and said other crank means being such that when the other crank means is nearest to the second shaft the second flexible member operatively engages the portion of the cam most remote from its axis and approaches its axis as the other crank means recedes from the second shaft, a propeller on said propeller

shaft, said propeller including a hollow hub portion having a pair of axially aligned blade shafts thereon, a feathering reaction blade mounted on each blade shaft, a crank arm on each blade shaft, said propeller shaft being hollow, a rod being mounted to move in said hollow propeller shaft, a pair of links pivoted to the rod and pivoted to the crank arms, a bearing disposed about said propeller shaft, links connecting the outer elements of said bearing to said pivoted arm shaft, a sleeve on said propeller shaft and connected to the inner element of said bearing, said shaft having opposed slots therein, and a pin connecting said rod and said sleeve and extending through said slots.

HARDY H. RAULERSON.
